UNITED STATES PATENT OFFICE

171,232

NEON TUBE ADVERTISING SIGN

Carl G. A. Roseñ, Peoria County, Ill.

Application January 3, 1952, Serial No. 17,908

Term of patent 14 years

(Cl. D1—12)

To all whom it may concern:

Be it known that I, Carl G. A. Roseñ, a citizen of the United States, residing in the county of Peoria, State of Illinois, have invented a new, original, and ornamental Design for a Neon Tube Advertising Sign, of which the following is a specification, reference being had to the accompanying drawing forming a part thereof.

Referring to the drawing:

Figure 1 is an elevational view of a neon tube advertising sign, showing my new design, and

Figure 2 is a side elevational view of the sign shown in Figure 1.

I claim:

The ornamental design for a neon tube advertising sign, as shown.

CARL G. A. ROSEÑ.
